WATER COOLER

Walter P. Hill, Pontiac, Mich.

Application December 7, 1951, Serial No. 260,400

5 Claims. (Cl. 62—141)

1

This invention relates generally to water coolers and more particularly to an improved unitary refrigerant or cooling unit.

It is an object of this invention to provide an improved unitary refrigerant unit which is adapted to be placed in and encompassed by a housing or body structure to provide an attractive water cooler.

It is a still further object of this invention to provide a refrigerating unit of the aforementioned type, in which water flowing therethrough from a conventional water supply source will be cooled to the desired temperature in a short period of time and through a minimum length of evaporator tubing.

It is a still further object of this invention to provide in a refrigerating unit of the aforementioned type, an evaporator, condenser and compressor interconnected with and arranged relative to each other in such a manner as to obtain the maximum refrigerating or cooling efficiency.

It is a still further object of this invention to provide an improved evaporator in which the refrigerant and water tubes are constructed and arranged relative to each other to provide maximum water cooling efficiency.

It is a still further object of this invention to provide a supporting frame structure for supporting the elements of the refrigerating unit in a simple, inexpensive and improved manner and so as to permit the refrigerating unit to be removed from, or inserted into a decorative housing, in a simple and speedy manner.

These and other objects of this invention will become apparent from the following detailed description, taken in conjunction with the accompanying drawing, in which:

Figure 1 is a front elevational view of a water cooler embodying the refrigerating unit of this invention;

Figure 2 is a rear elevational view of the structure illustrated in Figure 1;

Fig. 3 is an enlarged sectional view of the structure illustrated in Figure 1, taken along the line 3—3 thereof;

Fig. 4 is an enlarged sectional view of the structure illustrated in Figure 1, taken along the line 4—4 thereof;

Fig. 5 is an enlarged sectional view of the structure illustrated in Fig. 4, taken along the line 5—5 thereof; and

Fig. 6 is a sectional view of the structure illustrated in Fig. 5, taken along the line 6—6 thereof.

Referring now to the drawing, it will be seen that the water cooler embodies a suitable housing

or body 7, in which the refrigerating unit 9 of this invention is disposed. The housing 7 is supported on a base 11, in any suitable manner. The front wall of the housing 7 is provided adjacent the bottom thereof, with a plurality of air vents 13, and the back wall of the housing 7 has an opening therein covered by a plate or door 15. The plate or door 15 has air vents 17 adjacent the upper end thereof and air vents 19 adjacent the lower end thereof, disposed in an opposed relationship to the front wall air vents 13. The back wall of the housing 7 also has an opening 21 therein, through which a conduit extends to connect the refrigerating unit with a conventional water supply source, and a second opening 23, through which water may drain from a suitable bowl 25, supported in the upper end of the housing 7. A drinking spout 27 is disposed above the top of the housing 7 and bowl 25, and suitable actuating means are, of course, provided to permit the water to be turned on and off.

The refrigerating unit 9 is of the unitary type, that is, all of the elements of the refrigerating element are carried by a supporting framework 29. The supporting framework includes a pair of opposed vertically extending posts or straps 31, which have their lower ends rigidly and detachably connected at 33 with the bottom wall 35 of the housing 7, adjacent the base 11. Connected with the supporting framework 29, adjacent to the housing air vents 13 and 17, at the bottom of the housing, is a condenser 37 of any suitable or well known type. Supported above the condenser 37 is a fan 39, the blades of which are surrounded by a shroud 41. The fan 39, of course, incorporates a suitable motor which, when plugged into an electric source, causes the blades to draw air upwardly through the condenser coils, and because of the housing lower vents 13 and 19 and the upper vent 17 an induction draft effect is obtained, which aids in an efficient flow of air upwardly through the condenser. A suitable compressor 43 is connected with the framework 29 at 45 above the fan 39 and condenser 37. By mounting the compressor above the fan and condenser, the condenser is more efficiently cooled than if the compressor and condenser locations were reversed, wherein the hot air from the compressor would be blown over the condenser coils.

Supported above the compressor on the framework 29 is an evaporator 47, which is completely enclosed by insulating material 49. The evaporator is, of course, provided with suitable expansion valves and the like, and includes a coil of tubing 51 which surrounds and is concentric

with an inner coil of tubing 53. The tubing 53 carries water through the evaporator from the suitable water supply source to the drinking spout 27. A reservoir tank may be provided between the drinking spout and the outlet end of the tube 53, or the tube 53 may be of a large enough diameter to provide a reservoir of cool water so that when the water spout is actuated, the user will always have cool water to drink.

It should at this time be noted that the tubing 53 is of the finned tube type, wherein a plurality of fins extend around and along the entire length of the tubing 53 in closely spaced relationship relative to each other. Finned tubing in and of itself is well known and further description thereof is not thought to be necessary. It should, however, be pointed out that the tubing 53 is preferably constructed so that the outer portions thereof or the portions thereof exposed to refrigerant, such as Freon, which flows in the outer tubing 51, have approximately three times as much surface so exposed as the inner periphery or inside diameter of the tubing, for a reason which will be hereinafter pointed out. As in most refrigerating systems, the outlet of the condenser 37 is connected by a suitable conduit 57, including a suitable capillary tube portion which acts as an expansion member, to the inlet end of the evaporator 47. The outlet end of the evaporator outer tubing 51 is connected with the inlet end of the compressor by a suitable conduit 59. The output side of the compressor is in turn connected with the inlet end or top of the condenser by a suitable conduit 61, to provide an operating refrigerating or cooling unit.

A drain 63 is provided in the bottom of the drinking bowl 25 and connected with the drain for carrying waste water from the bowl is a pipe or precooler 65. The precooler extends downwardly through the evaporator and out through the opening 23 in the back wall of the housing 7. The conduit 57, which extends from the condenser to the inlet end of the evaporator, contacts the precooler or drain pipe 65 so that the refrigerant liquid is precooled by the draining water before it goes into the evaporator. Such precooling, of course, aids in providing a more efficient refrigerating or cooling system and prevents flashing and the waste of any of the refrigerant in the evaporating cycle.

It was previously pointed out that the evaporator water tube 53 was of a finned construction so as to have approximately three times as much surface exposed to the Freon as the inside diameter of the tube through which the water is flowing. This ratio of three to one has been chosen because the relationship between the condensing film coefficient of a refrigerating liquid such as Freon, and water is approximately three to one. This results from the fact that if the condensing film coefficient of water is taken as a standard, at 1,000, the condensing film coefficient of freon is approximately 350. Therefore, the ratio between the condensing film coefficients of these two liquids is approximately three to one. Therefore, by maintaining substantially the same ratio between the outside surface and inside surface of the evaporator water tube, a balanced system is obtained and the water can be cooled to its desired temperature through a shorter lineal length of tubing. As a matter of fact, it has been determined that 9.8 feet of finned tubing of the aforementioned type can transfer 12,000 B. t. u. of heat per hour, while it takes

24.4 feet of plain surfaced tubing to transfer the same number of B. t. u. per hour.

It will thus be seen that an improved water cooler construction is provided, in which the refrigerating or cooling unit is of the unitary type wherein it can be removed from or inserted into a housing as a complete unit and all of the elements of which are carried on a suitable supporting framework structure. It will furthermore be appreciated that a more efficient water cooler is provided in view of the arrangement and relationship between the compressor, condenser and evaporator and because of the provision of air vents adjacent the bottom of the cooler so that the elements may be more efficiently cooled and the temperatures thereof maintained at a minimum.

Still further it will be appreciated that an improved evaporator is provided, in which the water is cooled in a more rapid manner and through a shorter lineal length of tubing. Thus, the water cooler of this invention is not only more efficient in all stages of its operation, but is more easily handled and more compact and rigid in construction than such units heretofore provided.

What is claimed is:

1. A water cooler unit adapted to be enclosed by housing means and connected with a water supply source, including a supporting frame structure, a condenser supported by said structure and adapted to be disposed adjacent an air inlet opening in the housing means adjacent the bottom thereof, a fan disposed above said condenser for drawing air therethrough and directing the same upwardly, a compressor supported on said structure above said fan and connected with said compressor, an evaporator supported on said structure above said compressor, insulating means sealing off said evaporator from the portion of the housing therebelow, an air outlet in said housing below said insulating means, said evaporator including a tube having a finned outer periphery through the interior of which water flows, one end of said tube being connectable to the water supply source and the other end providing a water outlet, a second tube surrounding said water tube in spaced relation thereto and connected with said compressor and said condenser, through which refrigerant is adapted to flow to cool the water in the inner evaporator tube.

2. A water cooler unit adapted to be enclosed by housing means and connected with a water supply source, including a supporting frame structure, a condenser supported by said structure and adapted to be disposed adjacent an air inlet opening in the housing means adjacent the bottom thereof, a fan disposed above said condenser for drawing air therethrough and directing the same upwardly, a compressor supported on said structure above said fan and connected with said condenser, an evaporator supported on said structure above said compressor, insulating means enclosing said evaporator, said evaporator including a tube having a finned outer periphery through the interior of which water flows, one end of said tube being connectable to the water supply source and the other end providing a water outlet, a second tube, surrounding said water tube in spaced relation thereto and connected with said compressor and said condenser, through which refrigerant is adapted to flow to cool the water in the inner evaporator tube, said first tube having approximately three times as much area exposed to the refrigerant flow-

ing through said outer evaporator tube as said first tube has inner area exposed to the water flowing therethrough.

3. A water cooler including a cooling unit enclosed by housing means, a supporting frame structure disposed in said housing means and removably connected therewith, a condenser supported by said structure and disposed adjacent the bottom of said housing means, said housing means having an inlet opening adjacent the bottom thereof and said condenser and an outlet opening disposed above said condenser, a fan supported on said supporting structure and disposed above said condenser for drawing air therethrough and directing the same upwardly out through said housing outlet opening, a compressor supported on said supporting structure above said fan, an evaporator supported on said supporting structure above said compressor, insulating material sealing off said evaporator from the portion of the housing therebelow, said evaporator including a tube having a finned outer periphery through which water is adapted to flow, one end of said tube being connectable to a water supply source and the other end providing a water outlet, a bowl supported on said housing means above said evaporator, a drinking spout supported on said housing means and connected to said evaporator water tube, an outlet conduit communicating with the bottom of said bowl and extending downwardly through said evaporator for carrying away water in said bowl, said evaporator including a second tube surrounding said finned water tube in spaced relation thereto, said second tube being connected with said compressor and said condenser for carrying refrigerant to cool the water in the inner water tube.

4. A water cooler including a cooling unit enclosed by housing means, a supporting frame structure disposed in said housing means and removably connected therewith, a condenser supported by said structure and disposed adjacent the bottom of said housing means, said housing means having an inlet opening adjacent the bottom thereof and said condenser and an outlet opening disposed above said condenser, a fan supported on said supporting structure and disposed above said condenser for drawing air therethrough and directing the same upwardly out through said housing outlet opening, a compressor supported on said supporting structure above said fan, an evaporator supported on said supporting structure above said compressor and above said outlet opening, insulating material sealing off said evaporator from the portion of the housing therebelow, said evaporator including a tube having a finned outer periphery through which water is adapted to flow, one end of said tube being connectable to a water supply source and the other end providing a water outlet, a bowl supported on said housing means above said evaporator, a drinking spout supported on said housing means and connected to said

evaporator water tube, an outlet conduit communicating with the bottom of said bowl and extending downwardly through said evaporator for carrying away water in said bowl, said evaporator including a second tube surrounding said finned water tube in spaced relation thereto, said second tube being connected with said compressor and said condenser for carrying refrigerant to cool the water in the inner water tube, a portion of said evaporator refrigerant tube contacting said drain conduit so that cool water draining said conduit will cool the refrigerant flowing through said second tube.

5. A water cooler including a cooling unit enclosed by housing means, a supporting frame structure disposed in said housing means and removably connected therewith, a condenser supported by said structure and disposed adjacent the bottom of said housing means, said housing means having an inlet opening adjacent the bottom thereof and said condenser and an outlet opening disposed above said condenser, a fan supported on said supporting structure for drawing air through said condenser and directing the same upwardly out through said housing outlet opening, a compressor supported on said supporting structure above said fan, an evaporator supported on said supporting structure above said compressor, insulating material surrounding said evaporator, said evaporator including a tube having a finned outer periphery through which water is adapted to flow, one end of said tube being connectable to a water supply source and the other end providing a water outlet, a bowl supported on said housing means above said evaporator, a drinking spout supported on said housing means and connected to said evaporator water tube, an outlet conduit communicating with the bottom of said bowl and extending downwardly through said evaporator for carrying away water in said bowl, said evaporator including a second tube surrounding said finned water tube in spaced relation thereto, said second tube being connected with said compressor and said condenser for carrying refrigerant to cool the water in the inner water tube, said first tube having approximately three times as much area exposed to the refrigerant flowing through said outer evaporator tube as said first tube has inner area exposed to water flowing therethrough.
